TEACHING AID FOR TELLING TIME

Mable A. Golden, North Liberty, Ind.

Application July 28, 1958, Serial No. 51,962

Term of patent 7 years

(Cl. D25—1)

FIG. 2

FIG. 1

FIG. 3

Fig. 1 is a front elevational view of a teaching aid for telling time, showing my new design;

Fig. 2 is an edge elevational view thereof; and

Fig. 3 is a rear elevational view thereof.

The dominant features of my design reside in the portions shown in full lines.

I claim:

The ornamental design for a teaching aid for telling time, substantially as shown and described.
